UNITED STATES PATENT OFFICE

2,533,238

CIRCUIT CONTROLLER

Joseph F. Frese, Baltimore, Md., assignor to The Monitor Controller Company, Baltimore, Md., a corporation of Maryland

Application August 31, 1945, Serial No. 613,736

15 Claims. (Cl. 200—153)

1

My invention relates broadly to oil switches and more particularly to an improved construction of maintained contact type of oil switch.

One of the objects of my invention is to provide a construction of oil switch in which maintained contacts may be made or broken in a submerged pool of oil and in which the contact surfaces may be readily renewed or replaced from time to time.

Still another object of my invention is to provide an improved construction of maintained contact type of oil switch in which sleeve-like contact members are arranged to be projected or retracted from bridging connection with contact members under a submerged pool of oil.

Another object of my invention is to provide an oil switch of the maintained contact type in which readily replaceable plunger-like members and readily replaceable coating contacts are supported in submerged position in an oil bath and movement imparted to the plunger-like members for moving said members to either of two limiting positions for establishing a maintained connection with the coating submerged contacts.

Still another object of my invention is to provide an improved construction of oil switch of the maintained contact type in which an angularly shiftable actuator external to an oil filled casing is arranged to impart axial movement to sleeve members of insulation material carrying conductive bands operative to establish bridging connection with coating fixed contacts.

Still another object of my invention is to provide a construction of maintained contact type of oil switch in which a multiplicity of spaced contact members may be moved to either of two limiting positions with respect to coating fixed contacts within an oil pool, the movable and fixed contacts each being arranged for ready replacement or renewal.

Still another object of my invention is to provide a construction of actuator for effecting alternate longitudinal displacement of movable contact members with respect to spaced coating fixed contacts in which an angularly displaceable rack contacts with a pair of annularly grooved members extending from the movable contact members for effecting alternate displacement thereof.

Other and further objects of my invention reside in the novel construction of replaceable fixed and movable contacts in an oil switch of the maintained contact type as set forth more fully in the specification hereafter following by

2

reference to the accompanying drawings in which:

Figure 1 is a front elevational view of the oil switch of my invention; Fig. 2 is a rear elevational view on line 2—2 of Fig. 5 showing the terminal connections for the fixed contactors of the oil switch; Fig. 3 is a top plan view showing the mounting of the maintained type of oil switch on a terminal box, and the actuator thereof; Fig. 4 is a transverse sectional view taken substantially on line 4—4 of Fig. 1; Fig. 5 is a vertical sectional view taken substantially on line 5—5 of Fig. 1; Fig. 6 is a fragmentary vertical sectional view through the switch actuating mechanism taken substantially on line 6—6 on Fig. 5 and illustrating the limit locking means for the plunger members of the oil switch; Fig. 7 is a vertical sectional view on line 7—7 of Fig. 5 illustrating the segmentally toothed actuating member which engages with the grooves of the reciprocative plunger members for operating the switch; Fig. 8 is an elevational view of the bridging link which supports the switch locking mechanism; Fig. 9 is a transverse sectional view taken on line 9—9 of Fig. 8; Fig. 10 is a transverse sectional view taken substantially on line 10—10 of Fig. 6; Fig. 11 is a plan view of the segmentally toothed actuator which engages the grooved heads on the plunger members; Fig. 12 is a transverse sectional view taken on line 12—12 of Fig. 11; Fig. 13 is an elevational view of the limit locking mechanism for the plunger members of the oil switch; Fig. 14 is a longitudinal sectional view taken on line 14—14 of Fig. 13; Fig. 15 is a vertical sectional view showing a modified form of multiple contactor switch of the maintained contactor type embodying my invention; Fig. 16 is a vertical sectional view taken substantially on line 16—16 of Fig. 15; Fig. 17 is a transverse sectional view taken substantially on line 17—17 of Fig. 16; Fig. 18 is a detail view of one of the multiple contactors employed in the structure of Figs. 15 and 16; Fig. 19 diagrammatically illustrates the cooperative action of the roller members of the rocker with the cam faces of the locking latches of the switch mechanism; and Figs. 20A, 20B, 20C, 20D, and 20E, illustrate diagrammatically the various arrangements of contacts of the maintained type which may be employed in the oil switch structure of my invention.

Referring to the drawings in detail, reference character 1 designates a panel structure arranged to extend in a substantially vertical plane and attachable through suitable securing screws 2

with a terminal box represented at 3. The terminal box 3 is provided with suitable securing lugs 4 for attachment to a suitable supporting surface and is provided with a cable entrance represented at 5, through which cables may enter the terminal box leading to the oil switch. In Fig. 3 I have shown an alternative position for the cable entrance to the terminal box at 6. One of the important advantages of the oil switch construction of my invention resides in the fact that condensation, which might collect in the conduit leading to the terminal box 3 is obstructed from entering the oil switch contactor compartment illustrated generally at 7.

The panel 1 has an integrally connected panel 8 which extends in a plane substantially normal to panel 1. The panel 8 constitutes on its lower surface a cover for the oil container 9, while on its upper surface the panel member 8 has a housing 10 integrally connected therewith, said housing having the hollow interior thereof represented at 11, opening into the terminal box 3 to permit the passage of cables into the oil switch contactor compartment 7. The housing 10 serves as an enclosure and protecting means for the movable actuators of the switch mechanism. An extension 12 formed on housing 10 serves as a bearing means for angularly shiftable shaft member 14. Shaft member 14 extends externally of the housing 10 and has switch-actuating lever 15 secured thereto by suitable means, such as, transverse rivet member 16 which extends through lever 15 and shaft 14 to key the lever 15 to the shaft 14. The lever 15 has oppositely directed pressure-applying pallets 17 and 18 integrally connected therewith which may be alternately pressed manually for shifting the movable contactors within the compartment 7 from one condition to another condition.

The other end of shaft 14 extends interiorly of the housing 10 through the sealing washer 14a into the hollow section 11 thereof and through the resilient spacer washer 19, and the latch supporting plate 20 and between the locking latches 21 and 22 which are pivotally mounted thereon, to the rocker 23. Rocker 23 is keyed to the shaft 14 by suitable means, such as, transversely extending pin 24. The opposite ends of rocker 23 are segmentally shaped and are provided with teeth represented at 26 and 27. The teeth 26 and 27 are engageable with the grooved heads 28 and 29 of the respective plunger members 30 and 31, respectively.

The plunger members 30 and 31 each comprises single sections 30a and 31a connected to the sleeves of insulation material 43 and 44 respectively, by rivets 43a and 44a. The sections 30a and 31a are slideable through the detachable screw-threaded bushings, or guide members 32 and 33. The bushings 32 and 33 each have screw-threaded portions 32a and 33a which enter screw-threaded openings 34 and 35 in the panel member 8 forming the top of the contactor compartment 7. The screw-threaded bushings 32 and 33, and their associated plunger members 30 and 31, and grooved heads 28 and 29, constitute with the associated movable contact systems, assemblies which may readily be renewed or replaced from time to time as the movable contacts become worn. This is one of the outstanding advantages of the construction of my invention, in that the movable contact assembly may be renewed and replaced from time to time with or without the renewal of the co-acting fixed contacts carried by the replaceable panel structure

of insulation material represented generally at 36.

The bushings 32 and 33 are each provided with flanges 32b and 33b thereon which serve to clamp directly against the bridge member 37 for securing the bridge member 37 directly against the undersurface of panel 8. The bridge member 37 has a central slot 38 therein, which is locked directly beneath the open slot 39 in the panel member 8, to receive the tongue 20a of the latch supporting plate 20. The latch supporting plate 20 and the locking latches 21 and 22 are supported in immediate relation to the rocker 23 by the keying action between tongue 20a and the slot 38 in bridge member 37. The locking latches 21 and 22 are pivoted on latch supporting plate 20 at 21a, 22a but offset therefrom for distance sufficient to allow roller members 40 and 41, which are carried by rocker 23 to be engaged by the cam faces 21b and 22b of the locking latches 21 and 22, as represented, for example, in Fig. 19. The locking latches 21 and 22 are normally biased to a position in which the latches are drawn together by coil spring 42. As the rocker 23 revolves by rotation of shaft 14 by pressure applied against actuating pallets 17 or 18, the roller members 40 and 41 operate against the cam portions 21b and 22b of locking latches 21 and 22, and maintain the actuator 15 to the position in which it is displaced, and for correspondingly maintaining the electrical contactors within the compartment 7 in the position in which the contactors are displaced, until positively moved to an opposite position by positive pressure exerted against either of the pallets 17 and 18 in the position illustrated in Figs. 20A-20E. For example, roller 40 is latched above the cam portion 21b of lever 21, while roller 41 is latched below the cam portion 22b of lever 22. In order to shift rocker 23 to a reverse angular position, substantial pressure must be applied against pallet 18, thus avoiding undesired operation of the switch by a slight, or unintentional pressure directed against the actuator pallet 18.

Each of the movable contact assemblies includes a sleeve member of insulation material which I have represented at 43 and 44, secured to the sections 30a-31a of the plunger members 30 and 31 by suitable pins, as represented at 43a and 44a. The sleeves of insulation material 43 and 44 are each of such diameter that they will readily slide within the shell-like portions 32c and 33c of the detachable screw-threaded bushings, or guide members 32 and 33. These sleeves of insulation material 43 and 44 serve as carriers for any variety of contact arrangements of the types represented in Figs. 20A, 20B, 20C, 20D, and 20E. In Figs. 1-6 I have represented a two-pole contactor of the type symbolically shown in Fig. 20E where one contactor is open and the other closed in which operation of the switch actuator results in the opening of one contactor and the closing of the other contactor according to the arrangement of Fig. 20E. As represented in Fig. 1, the sleeve of insulation material 43 carries the conductive band 45 in a position in which it is displaced from bridging relation between the sets of fixed contactors represented at 46 and 47, when the switch-actuated lever 15 is in the position illustrated in Fig. 1. At the same time, the conductive band 48, which is carried by sleeve of insulation material 44 is disposed in shunt or bridging relation between contactors 49 and 50, as shown. It will be observed that, as pressure is applied to pallet 18 of switch-actuating lever 15, con-

ductive band 48 moves out of bridging relation with the co-acting fixed contacts 49 and 50, while conductive band 45 moves into bridging relation with coacting fixed contacts 46 and 47, thus closing two electrical circuits. The fixed contacts 46, 47, 49 and 50 consist of spring members which extend from supporting terminal strips 51, 52, 53 and 54, which are supported in spacial relation on insulated panel structure 36.

To preclude possibility of leakage between terminal strips 51 and 52 of opposite potential, I provide projecting surface portions on the panel 36 intermediate the terminal strips of opposite polarity. In Fig. 4 I have shown the enlarged opposite projected surface portions 55 and 56 of insulated panel 36 projecting in opposite directions between the terminal strips 51 and 52. In the case of terminal strips 53 and 54 enlarged surface portions of panel 36, as represented at 57 and 58, project in opposite directions from the panel 36 between the terminal strips 53 and 54 of opposite polarity. Thus, very substantial insulation is provided between the terminals of opposite polarity. Electrical connection is made to the terminal strips 51, 52, 53 and 54 by means of conductors anchored beneath the terminal screws 59, 60, 61, and 62. The panel of insulation material 36 is removably secured in a vertical plane to the undersurface of panel 8 by means of the removable and replaceable screw-threaded bolts 63 and 64. The removable and replaceable bolts 63 and 64 pass through longitudinally extending apertures 65 and 66 in the enlarged surface portions 55-56, and 57-58 of the panel 36, which are slotted at 56a and 58a, respectively.

The conductive bands 45 and 48 are each inclined at their opposite peripheral edges so that axial, or longitudinal movement of the plunger members 30 and 31 have the effect of slightly spreading the co-acting fixed resilient contacts 46, 47, 49 and 50, permitting substantial contact to be maintained between the respective conductive bands and the co-acting fixed contact. The structure of the co-acting fixed contacts is shown more particularly in Fig. 5 as comprising a substantially triangularly shaped bracket structure, such as is represented at 59, slotted at 50a to impart resiliency to the contactor which is mounted on the terminal strip 54. The entire panel of insulation material 36, and the intermediate enlarged surface 55-56, and 57-58 constitute a readily removable and replaceable unit which can be detached, or connected to the undersurface of the panel member 8, as indicated by the screw-threaded ends of the bolts 63, and 64 at 63a, and 64a as they pass through the panel member 8. This permits the fixed contactor assembly to be renewed and replaced from time to time, as the fixed contacts become worn.

The entire contact assembly, including both the movable and fixed contactors, are maintained in a pool of oil contained in the tank or casing 9 which is secured by means of screws 65 which pass through the panel member 8. The terminals 59, 60, 61 and 62 are all maintained above the level of the pool of oil, while the movable contactors 45 and 48, and the fixed co-acting contactors 46, 47, 49 and 50, are maintained below the level of the oil for quenching of the arcs which may occur therebetween. The cables from terminal box 3 pass through housing 11, and from housing 11 through a cable entrance in panel member 8 to establish connection with the terminal screws 59, 60, 61 and 62.

As shown in Figs. 15-18, the switch system of my invention may be readily applied to a double contactor system. In this arrangement, two panels of insulation material are arranged 5 symmetrically on opposite sides of the movable contact assemblies. I have represented one such insulated panel at 66, and the other insulated panel at 67. Panel 66 carries terminal strips 68, 69, 70, and 71, to which there is secured the 10 resilient contactors 72, 73, 74, and 75, which have conductive faces, shaped to establish engagement and electrical connection with the movable contactors. Provision is made for the insulation of the contactors of opposite polarity 15 by the enlarged surfaces of insulation material represented at 76-77, and 78-79. The removable bolt members 80 and 81 enable the panel of insulation material 66 to be readily removed and replaced.

20 Similarly, the panel of insulation material 67 provides supporting means for terminal strips 82, 83, 84, and 85, to which resilient contactors 86, 87, 88, and 89 are connected. The plunger members 30, and 31, carrying insulated sleeves 43, and 25 44 are reciprocative between the co-acting sets of fixed contactors. In this arrangement the movable contactors comprise sleeve members 90 and 91, and 92 and 93 separated by a disc member of insulation material represented at 94, and 30 95, respectively. This arrangement permits conductive sleeve 92 to be moved between stationary contactors 86, and 87, while conductive sleeve 93 is withdrawn from bridging relation between fixed contactors 72, and 73. Simultaneously, conductive sleeve 90 would be withdrawn from bridging relation with contactors 88 and 89, while conductive sleeve 91 would be moved to conductive bridging relation with contactors 74, and 75.

In the arrangement illustrated in Fig. 16, 40 rocker 23 operates to shift plunger member 30 upwardly, and move plunger member 31 downwardly to affect the circuit transfer above explained. The arrangement illustrated in Figs. 15-17 shows the relationship of movable and fixed contactors 45 for a condition in which one set of contactors are maintained normally open, while another set of contactors are maintained normally closed, which is the condition illustrated in Fig. 20E.

Fig. 20A shows a condition in which a set of 50 contactors, normally maintained in open circuit condition, may be conditioned to closed circuit condition upon movement of the maintained type of plunger member.

Fig. 20B illustrates the condition where a set 55 of contactors are normally maintained closed, and are opened by movement of the plunger members.

Fig. 20C illustrates a construction of switch in 60 which two sets of contacts are normally maintained closed, but are opened by displacement of the movable contact assembly.

Fig. 20D illustrates a condition in which two sets of contacts are normally maintained open, but are bridged by displacement of removable 65 contact assemblies.

Fig. 20E, as aforesaid, illustrates a condition 70 which is composite in character with respect to the arrangement of Figs. 20C, and 20D, that is, wherein one set of contacts are maintained closed, while the other set of contacts are maintained open, and wherein the reversed condition may be effected by displacement of the plunger member.

The grooved heads 28 and 29, which engage with the teeth 26 and 27 in the opposite ends of 75 rocker 23, are free to turn within the gear teeth

26 and 27 without advancing in their longitudinal position, whereby the conductive bands 45 and 48 are slowly rotatively moved. Thus, a fresh conductive surface is presented to the stationary contactors progressively, thereby extending the life of the contact system. The fact that the parallel grooves on grooved heads 28 and 29 may be axially revolved while remaining in engagement with the gear teeth 26 and 27 on rocker 23 enables a maintenance adjustment to be made of each of the plunger members 30 and 31 in order to present a fresh surface contact between the movable contact assemblies and the fixed contacts. This axial adjustment may be made throughout the entire angular distance of 360° in a plane transverse to the movable and fixed contact assemblies in either the projected or retracted positions of the plunger members. The fact that the guide members 32 and 33 have shell-like portions 32c and 33c surrounding the sleeves of insulation material 43 and 44 insures the precision axial movement of the plunger members 30 and 31 and the accurate registration of the movable contacts with the stationary contacts.

The fact that the parts of the switch of my invention may be readily removed, replaced and installed makes it possible for a customer or user to purchase the elemental parts of the switch and make the installation in the field in accordance with the requirements of a particular problem.

I realize that other contact arrangements may be provided in the maintained type of oil switch illustrated herein, and I desire that it be understood that such modifications are to be included within the scope of my invention and that no limitations upon my invention are intended other than may be imposed by the appended claims.

What I claim and desire to secure by Letters Patent of the United States is as follows:

1. Control mechanism for a switch comprising a housing, a set of fixed contactors insulatingly and removably supported by said housing on substantially spaced parallel axes, a pair of movable contact assemblies replaceably supported in said housing adjacent said fixed contactors, said movable contact assemblies each including a reciprocative plunger member, an insulation member connected therewith, a contact supported by said insulation member, a head connected with each of said plunger members, annular grooves formed on each of said heads and a rocker mounted for pivotal movement between the heads of said plunger members, said rocker having peripheral teeth on the opposite ends thereof engageable with the annular grooves in said heads for selectively and alternately linearly shifting said plunger members to positions in which the contact carried by said insulation members may be selectively connected with or disconnected from said co-acting fixed contactors the annular grooves of said heads being unrestrictedly revolvable within the teeth of said rocker.

2. Control mechanism for an electrical switch comprising a housing, a pair of replaceable movable contact assemblies supported on substantially spaced parallel axes by said housing, a plunger member individual to each of said movable contact assemblies and extending through said housing, a cylindrical head on each of said plunger members provided with a multiplicity of parallel spaced annular grooves, a rocker pivotally mounted externally of said housing in a position intermediate said cylindrical heads, said rocker having segmentally arranged teeth on

each end thereof engageable with the spaced annular grooves in each of said cylindrical heads, means external to said housing connected with said rocker for shifting said rocker to either of two limiting positions and imparting longitudinal movement to each of said plungers without restricting the revolvability of said movable contact assemblies, contacts carried by each of said movable contact assemblies, and co-acting fixed contactors carried by said housing, said contacts and fixed contactors being connected, or disconnected according to the linear movement of said plunger members.

3. Control mechanism for an electrical switch comprising a housing, a pair of replaceable movable contact assemblies, supported by said housing on spaced substantially parallel axes, a plunger member individual to each of said movable contact assemblies and extending through said housing, a cylindrical head on each of said plunger members provided with a multiplicity of spaced annular grooves, a rocker pivotally mounted in a position intermediate said cylindrical heads, said rocker having segmentally arranged teeth on each end thereof engageable with the spaced annular grooves in each of said cylindrical heads, means for shifting said rocker to either of two limiting positions and imparting longitudinal movement to each of said plungers without restricting the revolvability of said movable contact assemblies, contacts carried by each of said movable contact assemblies, co-acting fixed contactors carried by said housing, said contacts and fixed contactors being connected, or disconnected according to the movement of said plunger members, and means for latching said plunger members at either limit of the respective linear movement thereof.

4. Control mechanism for an electrical switch comprising a housing, a pair of replaceable movable contact assemblies supported by said housing on spaced substantially parallel axes, a movable and revolvable plunger member individual to each of said movable contact assemblies and extending through said housing, a cylindrical head on each of said plunger members provided with a multiplicity of spaced annular grooves, a rocker pivotally mounted in a position intermediate said cylindrical heads, said rocker having segmentally arranged teeth on each end thereof engageable with the spaced annular grooves in each of said cylindrical heads, means for shifting said rocker to either of two limiting positions and imparting longitudinal movement to each of said plungers without restricting the revolvability of said movable contact assemblies, contacts carried by each of said movable contact assemblies, co-acting fixed contactors carried by said housing, said contacts and fixed contactors being connected, or disconnected according to the movement of said plunger members, and a pair of yieldably latching levers associated with said rocker for locking said plunger members in either of the limits of the paths of movement thereof.

5. Control mechanism for a switch comprising a housing, sets of fixed contactors removably supported on substantially spaced parallel axes on said housing, a pair of parallel spaced movable contact assemblies replaceably supported by said housing adjacent said fixed contactors, said movable contact assemblies including linearly reciprocative plunger members each having an annular grooved longitudinally extending portion on one end, and an insulated portion on the other end, a contact carried by each of the insulated

portions and arranged to be connected with, or disconnected from the co-acting fixed contactors, a rocker disposed intermediate the annular grooved longitudinally extending portions of said plunger members, teeth formed on each end of said rocker and engageable with the annular grooved longitudinally extending portions of said plunger members for imparting motion to said plunger members in opposite directions as said rocker is angularly shifted without restricting the revolvability of said movable contact assemblies, and a manually controllable actuator for imparting angular movement to said rocker.

6. Control mechanism for an electric switch including a housing, a pair of movable contact assemblies disposed on substantially parallel axes and replaceably supported by said housing, each of said movable contact assemblies including an insulated portion, sleeve-like contacts carried by the said insulated portions at spaced intervals thereon, a disc of insulation material disposed between said sleeve-like contacts, sets of co-acting fixed contacts disposed on substantially parallel axes and aligned with said movable contact assemblies and engageable with said sleeve-like contacts, and means for imparting selective reciprocative movement to said movable contact assemblies for selectively alternately shifting the sleeve-like contacts into, or out of electrical connection with, or from, the co-acting fixed contacts without restricting the angular movement of said movable contact assemblies throughout an angular distance of 360°, with said discs of insulation material interposed between said sleeve-like contacts and said fixed contactors.

7. Control mechanism for an electric switch including a housing structure, a pair of reciprocative plunger members having movable contact assemblies mounted thereon and coacting with sets of fixed contactors carried by said housing structure, an elongated cylindrical head on each of said plunger members, symmetrically disposed spaced flanges formed on each of said elongated cylindrical heads, a control shaft journaled in said housing structure in a position intermediate said elongated cylindrical heads, and a rocker plate carried by said control shaft and extending between said pair of reciprocative plunger members coplanar with the axes thereof, said rocker plate having segmental teeth on each end thereof, the segmental teeth in diagonally opposite portions of said rocker plate meshing with the spaced flanges at diagonally opposite ends of the spaced elongated cylindrical heads on said plunger members for projecting and retracting said reciprocative plunger members said members being individually angularly adjustable through 360° while being alternately projectable and retractile through said housing structure for controlling the connection and disconnection of said movable contact assemblies and said coacting sets of fixed contacts.

8. Control mechanism for an electric switch including a housing structure, a pair of reciprocative plunger members having movable contact assemblies mounted thereon and coacting with sets of fixed contactors carried by said housing structure, an elongated cylindrical head on each of said plunger members, symmetrically disposed spaced flanges formed on each of said elongated cylindrical heads, a control shaft journaled in said housing structure in a position intermediate said elongated cylindrical heads, a rocker plate carried by said control shaft and extending between said pair of reciprocative plunger members

coplanar with the axes thereof, said rocker plate having segmental teeth on each end thereof meshing with the spaced flanges formed on each of said elongated cylindrical heads the flanges on said heads being individually angularly adjustable through 360° while being alternately projectable and retractile through said housing structure, the segmental teeth in diagonally opposite portions of said rocker plate meshing with flanges at diagonally opposite ends of the spaced elongated cylindrical heads on said plunger members for controlling the connection and disconnection of said movable contact assemblies and said coacting sets of fixed contacts, and latching mechanism mounted on said housing structure for maintaining said plunger members in either of the projected or retracted positions thereof.

9. Control mechanism for an electric switch including a supporting structure and a pair of electrical contact members reciprocative therethrough, a rocker arm pivotally mounted on said supporting structure and operatively connected with said pair of electrical contact members, a pair of spaced cam devices carried by said rocker arm, a plate member mounted on said supporting structure, a pair of latching levers pivotally mounted on said plate member, inwardly directed detents on said levers disposed in the path of the cam members on said rocker arm, and spring means for yieldably drawing said lever members together and in engagement with said cam members, for yieldably maintaining the detents on said lever members on either side of said cam members on said rocker arm for yieldably retaining the rocker arm in either of two opposite limiting positions thereof for maintaining the selected position of said electrical contact members.

10. A contact assembly for electric switches comprising in combination with a housing a pair of alternately reciprocative contact assemblies replaceably supported by the housing, a bridge member extending between and positively spacing said contact assemblies, a plate member supported by said bridge member in a plane normal thereto and in a position spaced from said contact assemblies, a pair of latching levers pivotally mounted on said plate member, detents carried by the inner faces of said latching levers and directed toward each other, a rocker for controlling the alternately reciprocative movement of said contact assemblies and operative between said reciprocative contact assemblies in a plane parallel to but spaced from the plane of said plate member, cams carried by said rocker and projecting into the plane of the detents on said levers, and means urging said cams into yieldable engagement with the detents on said levers for yieldably latching said rocked in either of the limits of angular movement thereof.

11. A contact assembly for electric switches including a supporting structure, a sleeve member detachably mounted on the supporting structure and including a guide shell extending therefrom, a plunger member mounted for sliding movement through said sleeve member and axially through said guide shell in annular spaced relation thereto, a sleeve member of insulation material carried by said plunger member and slidably in said guide shell and terminating within said guide shell in spaced relation to the interior end thereof to permit sliding movement of said sleeve of insulation material under control of said plunger member, an electrical contact carried by said sleeve of insulation material and a fixed electrical contact carried by said supporting struc-

ture in the path of movement of the aforesaid electrical contact.

12. A contact assembly for electric switches including a supporting structure, a cylindrical shell open at one end thereof and detachably mounted at the other end on said supporting structure, a plunger member axially slidable through said cylindrical shell in spaced relation to the interior walls of said cylindrical shell, a sleeve of insulation material connected with the end of said plunger member and terminating short of the internal end of said cylindrical shell, said sleeve of insulation material conforming to the interior diameter of said shell and being slidable therein under control of said plunger member, a movable electrical contact carried by said sleeve of insulation material and a stationary contact mounted in insulated relation to said supporting member in alignment with the movable contact carried by said sleeve of insulation material.

13. A contact assembly for electric switches comprising in combination with a supporting structure a fixed contact mounted in insulated relation to said supporting structure, a cylindrical shell guide carried by said supporting structure in a position adjacent said fixed contact, a plunger member axially movable through said cylindrical shell guide, a sleeve of insulation material carried by the end of said plunger member in a position conforming with the interior diameter of said cylindrical shell guide and terminating short of the internal end of said cylindrical shell guide, a movable electrical contact carried by said sleeve of insulation material and operative to establish a connection and disconnection with respect to said fixed contact as said plunger member moves axially through said cylindrical shell guide.

14. Control mechanism for an electric switch actuator comprising a supporting structure, a removable sleeve mounted on said structure, a plunger member axially slidable through said

sleeve, a contact assembly in supporting relation to one end of said plunger member and an operating head carried by the other end of said plunger member, said operating head including a plurality of spaced parallel extending flanges operative to be engaged at a multiplicity of linearly spaced positions along the length thereof for imparting a sliding movement to said plunger member for displacing the plunger member with respect to said cylindrical shell guide.

15. In a switch actuator, an angularly revolvable control shaft, a rocker arm mounted on the control shaft, and having a cam member extending longitudinally from the face thereof on each side of said control shaft, a plate member supported in parallel spaced relation to the plane of said rocker arm, a pair of pivotally mounted levers carried by said plate member on the side thereof of adjacent the cam members on said rocker arm, detents carried by said lever members and operative to engage on either side of the cam members carried by said rocker arm and plunger members for yieldably drawing said lever members together for maintaining the detents thereon in the path of movement of said cam members whereby angular movement of said shaft may be arrested and maintained in either of two limiting positions thereof.
